UNITED STATES PATENT OFFICE.

SIDNEY SMITH, OF BRIDGEPORT, CONNECTICUT, ASSIGNOR TO THE HOLMES & EDWARDS SILVER COMPANY, OF SAME PLACE.

DESIGN FOR A SPOON, FORK, &c.

SPECIFICATION forming part of Design No. 23,163, dated April 3, 1894.

Application filed March 1, 1894. Serial No. 501,998. Term of patent 7 years.

To all whom it may concern:

Be it known that I, SIDNEY SMITH, a citizen of the United States, residing at Bridgeport, in the county of Fairfield and State of Connecticut, have invented and produced a new and original Design for Spoons, Forks, and Similar Articles; and I do declare the following to be a full, clear, and exact description of the same, reference being had to the accompanying drawings, forming a part thereof.

Figure 1 is a view of the upper or obverse side of a spoon embodying my novel design and Fig. 2 is a similar view illustrating the back or reverse side of my novel design which in this instance is embodied in a fork, the embodiment thereof in a spoon being indicated by dotted lines.

The leading features of my novel design consist of the shape and ornamentation of the obverse and reverse as herein described and shown. The outlines of both edges of the

handle are irregular curves the two edges not corresponding with each other. Both sides of the handle are ornamented with conventional roccoco ornamentation.

25

1 denotes the center which is plain and may be either flat or rounded, and 2 denotes conventional roccoco ornamentation. At the base of the handle on the obverse side I provide other ornamentation designated by 3 of the 30 same general character as the ornamentation on the wider portion of the handle.

What I claim is—

The design for a handle for spoons, forks and similar articles substantially as shown 35 and described.

In testimony whereof I affix my signature in presence of two witnesses.

SIDNEY SMITH.
